(57) **CLAIM**

The ornamental design for a battery powered refrigerator, as shown and described.

DESCRIPTION

FIG. 1 is a perspective view of a battery powered refrigerator showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The coordination indicators in the drawings are environment that form no part of the claimed design.

The broken lines in the drawings depict portions of the battery powered refrigerator that form no part of the claimed design.
